(57) **CLAIM**

The ornamental design for a mobile device case, as shown and described.

DESCRIPTION

FIG. 1 is front perspective view of a mobile device case;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The dash-dot-dash broken line shown in FIG. 3 represents a boundary of the claimed design. The dash-dash broken lines throughout the drawing figures depict unclaimed environment. The broken lines form no part of the claimed design.
